(57) **CLAIM**

We claim the ornamental design for a mounting system for monitors, as shown and described.

DESCRIPTION

FIG. 1 is a front view of a mounting system for monitors
FIG. 2 is a rear view of a mounting system for monitors
FIG. 3 is a top view of a mounting system for monitors
FIG. 4 is a bottom view of a mounting system for monitors
FIG. 5 is a view from the right side of a mounting system for monitors
FIG. 6 is a view from the left side of a mounting system for monitors; and,
FIG. 7 is a perspective view of a mounting system for monitors.

1 Claim, 7 Drawing Sheets
